Chas. Norton
Printer's Patent

The following is referred to in the above Patent (No. 7442) as being part of the same containing a description in the name of the said Charles Norton
of his improvements in the Printing Type Cutter, and the
power Double cylinder Printing Type.

As all where it may, occurs

It is known that Charles Norton of the City of New Haven has made and is purposing to put into operation a new arrangement & combination of the parts of the Double cylinder printing type which are found in the combined printing cylinder printing type, and the cylinder printing type, and the hand cylinder printing cylinder printing type, and the following is a copy of a note given to the Argus newspaper, back to the 24th inst., last, announcing the publication of a part of the Argus as a perspective view of the type, by a man named W. H. S. on and over showing the kind of apparatus.

Most of the parts corresponding parts are designated by the same name. Many of these parts are such as are also in the cylinder printing type of (England) of this Country, and are not therefore claimed as my invention, but are, nevertheless, for the purpose of explaining more fully the nature of my improvement. If they are two separate cylinders placed at a suitable distance from each other and the shafts acting on them in the form work of the machinery. The toothed wheel D. B. attached to one end of these cylinders are connected with them, they are regular size & of mechanism, as to mesh with each other, but are two separate heads for supporting the forms, which are connected together by an iron connecting piece on their undersides which separates them entirely from each other. They are moved back and forward by means of a rack & pinion in the same manner as in the well known type printing machine. The shafts are joined by the pinion of the cylinder D. B. and the two forms placed upon the two head supports, and when it is in a toothed wheel it is one of the

1442

of which the uppermost is a wheel C. The next upper is
the wheel of the wheel D, on the upper side of which is a wheel
E, on the upper side of which is a wheel F. Between the cylinder
G, G, for printing paper which every two lines from the lower to the
upper side of which it receives its first impression. It is a wheel
which is connected to the four cylinders, which is also only a
turning segment, seen in the spiraling of the wheel D. As a piece
fastened to the side of which is turned by a power intended to move the
machine. The pulling wheel is marked C.C. 688, and for connecting
the taper of this wheel to the wheel C, some hole or opening to receive them
is in the back board on which the taper of paper is first laid, whence the
sheet is caused to D, to be connected in succession to the cylinder
marked afterwards in the wheel R. The last with the function
of communicating motion to them, the inking
which are the same in principle as those employed in the Napier press.
The gearing of the driving wheel A of the two large gear wheels
as well of the cylinder D D. H. G. the way of using the taper and some
other parts, are the same in principle with those machines in use in
England & elsewhere & known under the name of Linen & Apple-garth
printing machine.

What I claim as new in my press is the combination of
part of the Napier printing machine which constitutes the last
appearance with the cylinder & such other parts of the invention
of the large & Apple-garth printing press as are employed in the re-
ceiving & carrying of the sheets
and墨水瓶
